UNITED STATES PATENT OFFICE.

THOMAS LUCIEN TALIAFERRO, OF CHICAGO, ILLINOIS, ASSIGNOR TO PHOENIX-
HERMETIC COMPANY, OF BROOKLYN, NEW YORK, A CORPORATION OF NEW
YORK.

COVER FOR JARS.

1,381,363.

Specification of Letters Patent. Patented June 14, 1921.

Application filed November 19, 1918. Serial No. 263,149.

To all whom it may concern:

Be it known that I, THOMAS LUCIEN TALIAFERRO, a citizen of the United States, residing at Chicago, in the county of Cook, 5 State of Illinois, have invented certain new and useful Improvements in Covers for Jars, of which the following is a description, reference being had to the accompanying drawing and to the figures of reference 10 marked thereon.

The invention relates to new and useful improvements in covers for jars, and more particularly to a metal cover having a depending flange which is adapted to frictionally grip the outer wall of the jar for holding the cover in place thereon.

Prior to my invention metal jar covers having a depending flange formed with an inwardly projecting bead for gripping the 20 outer wall of the jar have been made. It has been found in practice that it is difficult to make jars in which the outer surface of the mouth of the jar is formed on a true circle without any irregularities in the shaping thereof. Often the outer wall of the jar in cross section is slightly elliptical. It is difficult to secure proper frictional grip between a cover of the type above referred to and a jar wherein the outer wall is irregular in contour.

An object of the present invention is to provide a metal cover having gripping projections formed in the flange thereof, which are so constructed as to grip the jar 35 throughout a greater portion of its circular extent and which projections are so formed that each one may reshape itself to conform to any irregularities in the contour of the jar and thus bring about an efficient frictional grip on the wall of the jar by each projection.

In the drawings which show by way of illustration one embodiment of the invention—

45 Figure 1 is a view in side elevation showing the upper portion of a jar having my improved cover applied thereto;

Fig. 2 is an enlarged vertical sectional view through a portion of the same;

50 Fig. 3 is a similar view but showing one

of the inset gripping portions bent or reshaped to conform to an irregularity in the surface of the jar.

The invention is directed broadly to a metal cover for a jar, such as are used for 55 preserves, or the like, and which are preferably made of glass or some similar material. The jar has an outer vertical wall and a seat at the upper edge of the wall which is within the circular extent of the outer 60 wall. The cover is preferably formed of a single piece of metal and has a depending flange which is provided with a series of inset portions parallel with the lower edge of the flange and are adapted to frictionally 65 grip the outer wall of the jar to hold the cover in place. Below the inset portions the flange is preferably provided with a strengthening bead and the extreme lower edge of the flange is continuous and uniformly 70 curved. These inset portions are spaced from each other a slight distance so that they are independent and each portion may bend or reshape itself independently of the others and thus the inset portions will 75 conform to any irregularities in the contour of the outer wall and each portion will frictionally grip the jar and hold the cover in place.

Referring more in detail to the drawings, 80 I have shown a portion of a jar at 1 and this jar has an outer straight or vertical wall 2. The upper edge of the wall terminates in a seat 3. My improved cover for the jar consists of a top section 4, which has an integral depending flange 5. The extreme lower edge 6 of this flange is continuous and uniformly curved. At the lower edge the flange is formed with a bead 7 which strengthens the lower edge of the flange and 85 serves to preserve the circular shape thereof. The depending flange is formed with a series of inset portions 8, separated from each other by a straight section 9 of the flange, and these inset portions 8 are tapered inwardly from the lower edges thereof toward the upper edge thereof, so that each inset section has a gripping line 10 adjacent its upper edge. These inset portions are the 95 only parts of the flange which engage the 100

outer wall 2 of the jar, as clearly shown in Figs. 2 and 3 of the drawings. The cover is so proportioned that in crowding the cover on to the jar these inset portions will be 5 slightly bent or reshaped so as to frictionally grip the jar. If the jar is out of round—that is, slightly elliptical in cross section, then the projections which engage the jar at the maximum diameter of the jar will be 10 bent or flattened to a greater extent, while possibly the inset portion at the minor diameter of the jar will only have a snug frictional grip on the wall of the jar with little or no bending or reshaping.

15 In Fig. 2 of the drawings, I have shown the grip of the inset portion on the jar with little or no reshaping of the same, while in Fig. 3 of the drawings, I have shown the inset portion as flattened to a considerable degree. Through this bending of the metal in 20 each inset portion or the reshaping of the same, I have been able to construct a cover which will have a frictional grip on the outer wall of the jar throughout a greater 25 portion of its circular extent, so that the cover will be held firmly in place. The sections 9 separating the inset portions are of only sufficient extent to permit the inset portions to bend or reshape themselves independently, as above noted, and, therefore, 30 the cover grips the outer wall of the jar practically throughout its entire circular extent. This brings about a very efficient grip on the jar and holds the cover so firmly in 35 place that a sealing ring may be used in connection with the cover, if desired, and said sealing ring held firmly seated on the jar.

In Figs. 2 and 3 of the drawings, I have 40 shown the top section of the cover as bent upwardly, as at 11, to form a groove on the inner face thereof for a sealing ring 12 which may be made of any desired composition which can be caused to adhere to the cover and secured thereto by slightly heating the same and applying pressure thereto. 45 This sealing ring is adapted to engage the seat 3 at the upper edge of the wall of the jar and the cover will hold said sealing material pressed firmly against the seat 3 on 50 the jar.

It is obvious that minor changes in the 55 details of construction and the shaping of the parts may be made without departing from the spirit of the invention, as set forth in the appended claims.

Having thus described my invention, what I claim as new and desire to secure by Letters Patent, is:—

1. A metal jar cover comprising a top section 60 and a depending flange, said flange having inset portions at a distance above the lower edge of the flange for forming a relatively broad gripping contact with the jar walls throughout a greater portion of its 65 circular extent, said inset portions being

spaced sufficiently to permit the metal in each portion to bend or reshape itself independently of the other portions, so that the gripping surface of the cover may conform to irregularities in the surface or contour 70 of the jar.

2. A metal jar cover comprising a top section and a depending flange, said flange having inset portions at a distance above the lower edge of the flange for gripping the jar throughout a greater portion of its circular extent, said inset portions being spaced sufficiently to permit the metal in each portion to bend or reshape itself independently of the other portions, so that the gripping surface of the cover may conform to irregularities in the surface or contour of the jar, said inset portions providing gripping surfaces 80 continuous with the flange.

3. A metal jar cover comprising a top section and a depending flange having a continuous lower edge, said flange having integral inset portions at a distance above the lower edge of the flange for gripping the jar throughout a greater portion of its circular 90 extent, said inset portions being spaced sufficiently to permit the metal in each portion to bend or reshape itself independently of the other portions, so that the gripping surface of the cover may conform to irregularities in the surface or contour of the jar. 95

4. A metal jar comprising a top section and a depending flange, said flange having inset portions at a distance above the lower edge of the flange for gripping the jar throughout a greater portion of its circular extent, said inset portions being spaced sufficiently to permit the metal in each portion to bend or reshape itself independently of the other portions, so that the gripping surface of the cover may conform to irregularities in the surface or contour of the jar, 100 said inset portions providing gripping surfaces continuous with the walls of the flange, the lower edge of said flange having a bead 105 formed therein for strengthening said edge.

5. A metal jar comprising a top section and a depending flange, said flange having inset portions integral with and at a distance above the lower edge of the flange for gripping the jar for a greater portion of its circular extent, said inset portions being spaced sufficiently to permit the metal in each portion to bend or reshape itself independently of the other portions, so that the gripping surface of the cover may conform to the irregularities in the surface or contour of the jar, said top section having the portion directly above the wall of the jar bent upwardly to form a groove on its inner 115 face for a sealing ring, and a sealing ring secured in said groove.

6. A metal jar comprising a top section and a depending flange, said flange having inset portions at a distance above the lower 120

edge of the flange comprising relatively long arcuate gripping surfaces spaced by relatively narrow flange walls whereby to provide a gripping contact throughout the 5 greater portion of the circular extent of the jar wall, said inset portions being spaced sufficiently to permit the metal in each por-

tion to bend or reshape itself independently of the other portions so that the gripping surface of the cover may conform to the 10 irregularities in the surface or contour of the jar.

In testimony whereof, I affix my signature.
THOMAS LUCIEN TALIAFERRO.
